UNITED STATES PATENT OFFICE.

OLIVER W. NICHOLS, OF DENVER, COLORADO.

FORM FOR GARMENTS.

1,052,615.

Specification of Letters Patent. Patented Feb. 11, 1913.

Application filed May 13, 1912. Serial No. 696,913.

To all whom it may concern:

Be it known that I, OLIVER W. NICHOLS, a citizen of the United States of America, residing at Denver, in the county of Denver and State of Colorado, have invented certain new and useful Improvements in Forms for Garments; and I do hereby declare the following to be a full, clear, and exact description of the invention, such as will enable others skilled in the art to which it appertains to make and use the same.

My invention relates to improvements in display forms for garments and more particularly to portable devices of this class particularly adapted to display gowns and like articles and its object is to provide a device whereby the garment contained within in a case may be displayed advantageously on all sides without removing it from said case, to provide a device enabling the garment to be folded within a case without injuring the garment, and to provide a device light in weight, cheap in construction, effective in operation and to provide the same with various other new and useful features hereinafter more fully described and particularly pointed out in the claims.

This display form consists essentially of a garment form adapted to be secured within in a case and constructed to allow the garment supported upon it to be folded wholly within the case or unfolded and displayed on all sides without detaching the said form from the case.

This device is also provided with various new and useful features of construction and arrangement, as will more fully appear by reference to the accompanying drawings, in which:

Figure 1 is a perspective view of a device embodying my invention shown opened in the position it would be when used to display a garment; Fig. 2 is the same with the form partially folded; Fig. 3 is a longitudinal section of the device fully folded and the lid of the case closed; and Fig. 4 is a transverse section through the bust portion of the garment form illustrating the means for obtaining the desired curvature for the bust.

Like numbers refer to like parts in all of the figures.

1 represents a suitable case preferably rectangular in shape and comparatively shallow in depth, provided with a removable cover 2 preferably hinged to the case at one end.

The garment form is composed of a waist member 3 and a skirt member 6 connected by a transversely divided and hinged middle member consisting of two substantially equal parts 4 and 5, the waist member 3 being hinged to the upper edge of the part 4 and the skirt member hinged to the lower edge of the part 5. All of these members which constitute the form are preferably made of heavy cardboard or other like substance and the hinges by which they are joined are preferably made of fabric glued to the said members the flexibility of the fabric affording the necessary hinge feature. The bust portion of the waist member is provided with cords or tapes 7 attached at opposite sides of the said portion and extending behind the same. By shortening these cords the bust portion of the form is caused to bend or spring outward more or less giving the same the desired curvature and the cords are then tied together to retain the form in this shape. When in use the part 4 of the middle portion is secured to the bottom of any suitable case substantially as described, preferably by a detachable or McGill fastener as at 8.

When the form is placed within the gown or garment to be displayed it is removed from the case by detaching the fastener 8 and after the garment has been arranged on the form the same is again placed within the case and the fastener is passed through the opening at the back of the gown and again attached to the bottom of the case. The device is now ready for use and when opened the gown may be displayed on all sides. The waist member may be inclined forward in order to show the back of the waist or the skirt member may be turned upward to display the back of the skirt. The double hinge feature of the skirt member of the form allows the skirt to be folded into the case without necessitating any sharp creases to be formed in the said skirt where it is folded, the part 5 of the middle portion serving to space apart the skirt member from the waist portion, and after the garment has been folded in the case and the cover of the same is closed the whole device and garment therein may be readily stored away or transported from place to place, or the garment exhibited as described without removal from the case.

What I claim is:—

1. A garment form, comprising a divided

and hinged middle portion, a waist portion pivotally attached to the upper edge of said middle portion, and a skirt portion pivotally attached to the lower edge of said middle portion.

2. A garment form, comprising a middle portion consisting of two parts hinged to each other, the upper part being fixed, a waist portion hinged to the upper edge of the fixed part of said middle portion, cords attached to opposite edges of the upper part of said waist portion extending behind the same and adapted to be drawn together to curve the upper part of the waist portion, and a skirt portion pivotally attached to the lower edge of said middle portion.

3. A garment form, comprising a fixed middle portion, a hinged middle portion adjacent thereto, a waist portion hinged to the upper edge of said fixed middle portion, cords attached to opposite edges of the

upper part of said waist portion extending behind the same and adapted to be drawn together to curve the upper part of the waist portion, and a skirt portion pivotally attached to the lower edge of said middle portion.

4. A garment form transversely divided into four portions hinged to each other in series, and comprising a waist portion, two middle portions, the upper one of which is adapted to be fixed in a case, and a skirt portion foldable opposite the waist portion and spaced apart therefrom by the other middle portion.

In testimony whereof I affix my signature in presence of two witnesses.

OLIVER W. NICHOLS.
